Application August 29, 1935, Serial No. 38,348

3 Claims. (Cl. 30—340)

This invention relates to improvements in knives. A knife embodying this invention is particularly adapted for use as a paring knife or carving knife.

It is the object of the invention to provide a knife with a handle having a specific relation to the blade and provided at a point spaced from the blade with a fin at a particular angle and adapted to lie between the forefinger and second finger of the user to be grasped between the forefingers and thereby to enhance the facility with which the operator may manipulate the knife.

In the drawing:

Figure 1 is a view in side elevation of a knife embodying the present invention.

Figure 2 is a view thereof in plan.

Figure 3 is a section taken on line 3—3 of Fig. 1.

Figure 4 is an end elevation of the handle with the blade appearing in section on the line 4—4 of Fig. 2.

Like parts are designated by the same reference characters throughout the several views.

The particular form of the blade will obviously require variation to suit the particular use to which the knife is to be put. The knife illustrated is designed for use as a paring knife having a blade 5 with a substantially rectilinear cutting edge 6 and a curved back 7.

The particular handle illustrated is a moulded handle, the material of which flows integrally as shown at 8 through suitable openings provided in the shaft 9 of the blade.

The end of the handle is preferably bevelled rather sharply as shown at 10 so that the handle extends materially farther along the back edge 7 of the blade than it does along the cutting edge 6 thereof. This provides a support at the back 20 of the blade for the forefinger of the operator which enables the pressure of the operator's forefinger to be exerted much closer to the point of engagement of the blade with the work than would otherwise be conveniently possible.

At the opposite end of the handle there is preferably a head 11 which tends to confine the operator's hand to the handle. I preferably, though not necessarily, also provide ridges 12 and 13 of more or less conventional form at points spaced to receive the operator's fingers, whereby to improve his grasp on the blade. The ridge 13 lies between the second and third fingers and the ridge 12 between the third and fourth fingers of the operator's hand. While such ridges have heretofore been provided on knife handles

and the like, it will be noted that in the present device the head ridge 11 and the ridges 12 and 13 are convergent, and it will also be noted that the ridge 13 is elongated as compared with ridge 12 (see Fig. 1). There is, however, very little difference in the height of the ridges or their projection from the handle proper.

One of the important features of the invention consists in the web or fin 15 which is received between the operator's forefinger and second finger. This fin extends completely across one side of the handle and is distinctly different from the ridges 12 and 13 in that its projection from the face of the handle is sufficient to enable it to be grasped between the operator's first and second fingers. It is not only of considerable projection, but it is very thin so that it does not force the fingers materially apart. Like the ridge 13, it is convergent toward the ridge 11.

The outer margin 14 of the fin 15 is preferably substantially rectilinear as shown in Fig. 4 and one of the corners of the fin which appears at the top in Fig. 4 is more gradually rounded than the lower corner, the latter being almost rectangular.

The back face 16 of the handle is positioned to be engaged in the palm of the operator's hand and is preferably free of ridges and is convex in form and rather sharply rounded at 17 where it approaches the blade.

The form and extent of the fin 15 is such that it lies sufficiently far between the operator's fingers so that the knife may be grasped by the pressure of these fingers toward each other entirely apart from the engagement of the fingers about the handle proper. This fact has been found to contribute greatly to the maneuverability of such a knife, since it enables the operator freely to shift his grasp on the handle from time to time without dropping or even discontinuing his use of the knife.

Thus a continuous flexing of the hand is possible even during the most rapid use of the knife and the operator's fingers do not become cramped and tired as they do in the use of an ordinary knife which depends for its manipulation and retention upon the clasp of the operator's fingers tightly about the handle.

Furthermore, it is found that with a high fin at 15 immediately adjacent the portion of the handle engaged at 18 by the operator's forefinger over the back of the knife blade, a great firmness and precision in the use of the knife is possible. In many other knives, attempts have been made to limit the movement of the operator's

hand over the back of the blade by means of some sort of support located at the extreme end of the handle adjacent the blade. In such knives, however, there is not the freedom of manipulation nor the security of support that is provided by fixing the position of the operator's hand with a fin located between the first and second fingers instead of outside of the first finger.

I claim:

- 10 1. In a knife, the combination with a blade having a cutting edge and a back edge, of a handle connected with said blade and bevelled at its end to extend farther along the back edge than along the cutting edge of the blade, all sides 15 of said handle convexly approaching said blade, together with a fin mounted on said handle substantially wholly at one side thereof and projecting therefrom to a distance sufficiently to be engaged between the operator's first and second 20 fingers, said fin being continuous substantially completely across one side of the handle from portions of the handle aligned with the back of the blade to portions of the handle aligned with the cutting edge thereof.
- 25 2. In a knife, the combination with a blade

having a cutting edge and a back edge, of a handle connected with said blade and bevelled at its end to extend farther along the back edge than along the cutting edge of the blade, all sides 5 of said handle convexly approaching said blade, together with a fin spaced from the end of said blade for the width of the operator's forefinger and inclined with reference to said handle sufficiently to approach parallelism with the beveled end thereof.

3. The combination with a knife blade having a back and a cutting edge, of a handle connected with said blade and provided with a fin spaced from said blade upon said handle for approximately only the width of the operator's forefinger, 15 said fin projecting laterally from the handle sufficiently to be received between the operator's first and second fingers to facilitate his grip upon the handle in the manipulation of the knife, and said fin being substantially continuous with a relatively thin cross section across one side of the handle from that portion of the handle adjacent the back of the blade to that portion of the handle adjacent the cutting edge thereof.

WALLIE FOLTZ. 25
